UNITED STATES PATENT OFFICE.

GRANVILLE H. GRAY, OF LOS ANGELES, CALIFORNIA.

ROAD-SANDING APPARATUS.

1,165,331.

Specification of Letters Patent.

Patented Dec. 21, 1915.

Application filed March 9, 1914. Serial No. 823,375.

To all whom it may concern:

Be it known that I, GRANVILLE H. GRAY, a citizen of the United States, residing at Los Angeles, in the county of Los Angeles, State of California, have invented new and useful Improvements in Road-Sanding Apparatus, of which the following is a specification.

This invention relates to a road sanding apparatus.

It is the object of this invention to provide an apparatus for distributing sand on the surface of roadways, and it is the particular object of this invention to provide means for equally and uniformly distributing the sand.

A further object is to provide a pneumatic means for projecting the sand with force upon oiled roadways, whereby the sand will be thoroughly and rapidly embedded in the oil medium.

A further object is to provide means for regulating and controlling the discharge of sand from the spreading apparatus by which any desired amount of sand can be delivered and distributed according to the nature and requirements of the roadway.

Other objects will appear hereinafter.

The invention primarily resides in a sand discharging hopper formed with a plurality of discharge nozzles, means for regulating the flow of sand into the hopper and from the nozzles, means for forcing the sand from the nozzles by air pressure, and means for uniformly distributing the sand discharged from the nozzles over the road surface.

The invention is illustrated in the accompanying drawings, in which:

Fig. 1 is a side elevation of the road sanding apparatus, with parts removed. Fig. 2 is a view in elevation of the rear end of the apparatus with parts broken away. Fig. 3 is an enlarged detail section on the line 3-3 of Fig. 2. Fig. 4 is a detail section in a vertical plane at right angles to the section of Fig. 3.

More specifically, 5 indicates a truck frame provided with front and rear wheels 6 and 7 and fitted with a tiltable box body, which box body is pivoted to the frame 5 adjacent its rear end and is adapted to be rocked lengthwise from the position indicated in dotted lines in Fig. 1 to the position shown in full lines; the rocking of the body 8 being effected in any suitable man-

ner. The means for rocking the body 8 is here shown as including a cable 10 attached to a hanger 11 on the forward end of the body 8 and passing over pulleys 13 on a frame 14, which cable leads to a drum, not shown, controlled in any suitable manner. The rear end of the body 8 opens to a hopper 15, the top and bottom walls of which converge groundward and terminate in a plurality of discharge nozzles 16. The end 65 walls 17 of the hopper are shown as diverging outwardly to form the discharge end of the hopper of a length approximating the span of the wheels 7 of the truck. Hinged at 18 on the top member of the hopper 15 and extending throughout the width of the hopper is a gate 19, the lower edge of which gate is designed to abut against the rear end of the bottom of the body 8 to close the receiving end of the hopper 15 and prevent the 70 passage of sand thereinto from the body 8 when the sand is being conveyed to a point of discharge. The gate 19 is also provided for the purpose of regulating the flow of sand from the body 8 into the hopper 15, for 75 which purpose it is provided with an adjusting means by which it may be secured in various positions relative to the bottom of the hopper 15, whereby the space between the lower edge of the gate and the bottom of 80 the hopper may be varied in width according to the amount of sand it is desired to discharge into the lower portion of the hopper. This adjusting means is here shown as consisting of bolts 20 mounted on 85 each end of the gate 19 and passing through arcuate slots 21 formed in the ends 17 of the hopper concentric with the pivots of the hinges 18; the bolts 20 being threaded on their outer ends to receive nuts 22 by which 90 the ends of the gate 19 may be securely clamped to the ends 17 of the hopper. For the purpose of preventing leakage of the sand through the slots 21 shield plates 23 are attached to the upper faces of the gate 19 in such position as to normally extend over the slots 21 as illustrated in Fig. 3. Means are also provided for closing the aperture or space between the lower edge of the gate 19 and the bottom of the hopper 15 100 independent of the gate 19 for the purpose of temporarily cutting off the flow of sand into the lower portion of the hopper, as when turning the apparatus, or when moving from one point to another where it is 105 110

not desired to distribute the sand and where it would not be expedient to adjust the gate 19 to its closed position. This means comprises an auxiliary gate 24 hinged at 25 adjacent the lower edge of the gate 19 on its underside and extending throughout the length thereof. The auxiliary gate 24 is connected at its ends to hand levers 26 by means of links 27; the hand levers 26 being pivoted at 28 to the ends 17 of the hopper and extending outwardly therefrom through an opening 29 formed in the top of the hopper and extending the width thereof.

15 Mounted within the hopper is an agitator consisting of a revoluble shaft 30 on which a series of pins 31 is mounted; the shaft 30 extending through the ends 17 of the hopper and provided with sprocket wheels 32 engaging with sprocket chains 33 leading over 20 sprocket wheels 34 carried by the rear wheels 7 of the truck. This agitator operates when the truck is in motion to prevent the sand in the lower portion of the hopper from packing.

25 Mounted on the sides of the body 8 are air reservoirs 35 to which air is supplied under pressure through a flexible hose 36 from a compressor 37 of any suitable type operated in any suitable manner, and leading from the air reservoirs 35 are discharge pipes 38 which lead to a single pipe 39 through a regulating valve 40. The pipe 39 is fitted with a cut-off valve 41 and connects at its lower end with a horizontal manifold pipe 42 arranged adjacent the upper face of the hopper 15 and extending throughout the width thereof. Connecting with the manifold pipe 42 opposite each of the nozzles 16 are air discharge nozzles 43 fitted with regulating cut-off valves 44; the air discharge nozzles 43 extending into and terminating within the sand discharge nozzles 16, the discharge ends of the air nozzles 43 are directed diagonally to the discharge orifices of the 35 nozzles 16, as particularly shown in Fig. 3 so that the blasts of air therefrom will not be directed against the road surface when the apparatus is in operation, and whereby the sand passing from the nozzles 16 will be 40 sprayed upon the road surface with considerable force.

50 Supported on the rear end of the truck frame 5 is a spreading broom 45 carried on a horizontally extending frame 46 fitted with standards 47 at its ends, which standards are slotted at 48 and are adjustably engaged by bolts 49 on brackets 50 carried on the end of the truck frame 5. The slots 48 and bolts 49 provide a means by which the 55 spreading broom 45 can be adjusted vertically to vary its action. The frame 46 is connected to the hopper 15 by means of a chain 51, which chain acts to maintain the spreading broom 45 in proper relation to the 60 hopper when the apparatus is in operation.

and also forms a means for supporting the spreading broom clear of the road surface when the apparatus is not in operation.

When it is desired to distribute sand over the road bed the body 8 is rocked on its 70 pivot to the position shown in full lines in Fig. 1, so as to incline the bottom thereof and cause sand therein to be discharged into the upper end of the hopper 15; the gate 19 having been previously adjusted to permit 75 a required amount of the sand to pass beneath its lower end to the lower portion of the hopper and the auxiliary gate 24 retained in a closed position by the operator through the medium of the hand levers 26 80 until the truck is moved to the desired position. The truck is then advanced in the direction indicated by the arrow —a— in Fig. 1, and the hand levers are released to open the auxiliary gate 24 and permit the sand 85 to pass from the upper portion of the hopper into its lower portion where, by reason of the restricted nozzles 16, it accumulates as shown in Fig. 3, and discharges slowly 90 from the nozzles 16. Air under pressure being admitted to the manifold pipe 42 from the reservoirs 35 through the pipes 38 and 39 and the valves 40 and 41, will be discharged through the air discharge nozzles 43 into the body of sand in the nozzles 16, 95 thereby forcing and discharging the sand from the nozzles so as to drive it into the previously oiled surface of the road bed. In advancing the truck, the agitator shaft 30 will be rotated from the sprocket 34 on the 100 truck wheels 7 through the chain 33 and sprockets 32, thereby causing the fingers or pins 31 to pass through the sand in the hopper and thereby prevent it from packing, and choking in the hopper and insuring its 105 discharge therefrom. The spreading broom 45 being previously adjusted will operate as the apparatus advances to distribute the sand uniformly and prevent it from accumulating in uneven piles. When it is desired to stop and turn the vehicle the operator closes the gate 24 by operating the lever 26 to prevent the discharge of the sand into the hopper. To close the gate 19 the body 8 is restored to its normal horizontal 110 position; the bolts 49 being loosened to permit the broom frame 46 and standards 47 from rocking upwardly thereon to position the broom 45 clear of the ground, where it will be supported by the chain 51 and the 115 bolts 49. The nuts 22 on the bolts 20 are then loosened whereupon the operator can close the gate 19 by operating the lever 26 which lever will act through the links 27 and the gate 24 to actuate the gate 19; the 120 gate 19 being secured in its closed position by retightening the nuts 22.

What I claim is:

1. In a sand distributing apparatus, the combination of a pivoted box body, a 13

- groundward convergent hopper on the end thereof, a plurality of sand discharge nozzles on the lower end of said hopper, means for forcing the sand from said nozzles by air pressure, means in the hopper for regulating the flow of sand to said nozzles, and means for agitating the sand within the hopper.
2. In a sand distributing apparatus, a vertically and longitudinally tilttable truck body, a hopper affixed to the rear end thereof, a hinged gate within said hopper, means for rigidly holding said gate against movement in various adjusted positions to regulate or inhibit the flow of sand into said hopper, and an auxiliary gate hinged to the first named gate adapted to be operated independent thereof to prevent the entrance of sand into the hopper.
3. In a road sanding apparatus, a box body, a groundward convergent hopper affixed thereto, a plurality of sand discharging nozzles on said hopper, means for regulating the flow of sand from the box body to the nozzles, means for agitating the sand in the hopper, and air nozzles extending into the sand discharge nozzles, whereby the discharge of the sand from the nozzles may be accelerated by air pressure.
4. In a sand distributing apparatus, a tilttable box body, a hopper affixed to one end thereof, a hinged gate within said hopper, threaded members on the ends of said hinged gate extending through arcuate slots in the sides of the hopper adapted to receive nuts, whereby the gate is held rigidly against movement in various positions to regulate the flow of sand into said hopper, and an auxiliary gate hinged to the first-named gate adapted to be operated to prevent the entrance of sand into the hopper.

In witness that I claim the foregoing I have hereunto subscribed my name this 27th day of February, 1914.

GRANVILLE H. GRAY.
